UNITED STATES PATENT OFFICE.

THOMAS W. CORKELL, OF CHICAGO, ILLINOIS.

COLLAPSIBLE REEL-BARREL.

1,266,771.

Specification of Letters Patent. Patented May 21, 1918.

Application filed March 6, 1917. Serial No. 152,628.

To all whom it may concern:

Be it known that I, THOMAS W. CORKELL, a citizen of the United States, and a resident of the city of Chicago, in the county of Cook, and State of Illinois, have invented certain new and useful Improvements in Collapsible Reel-Barrels; and I do hereby declare that the following is a full, clear, and exact description of the same, reference being had to the accompanying drawings, and to the numerals of reference marked thereon, which form a part of this specification.

This invention relates to an improved form of an externally reinforced collapsible reel barrel, constructed of wood and metal, or other suitable materials, having a plurality of compartments therein through which axially disposed rotatable means project to permit materials to be simultaneously wound thereon in each of said compartments through a suitable opening afforded by opening up locking members at each end permitting certain of the barrel staves to be swung outwardly into an open position.

It is an object of this invention to construct a collapsible barrel having means rotatably mounted therein to permit materials to be wound thereon for shipment.

It is also an object of this invention to construct a collapsible barrel reinforced by an external link belt formed to permit the barrel to be readily tilted or turned while the same is being rolled.

It is a further object of this invention to provide a collapsible reel barrel adapted to be opened along one side to permit materials for shipment, to be placed therein.

It is an important object of this invention to construct a collapsible barrel having compartments formed therein through which a rotatable shaft projects to permit materials to be wound thereon for shipment, said barrel when closed adapted to have a link belt secured therearound to reinforce the barrel and permit the same to be readily pivoted on said link belt while the barrel is being rolled.

It is furthermore an object of this invention to provide an externally reinforced knock-down barrel constructed of wooden staves connected together by means of cables threaded therethrough and held in a cylindrical form by flanged metallic end heads being provided with hinged members

which when opened permit certain of the staves to be swung outwardly from the barrel to permit materials to be wound for shipment upon a rotatably mounted shaft, 60 journaled in said end heads and projecting through a plurality of compartments formed within the barrel.

It is also an important object of this invention to construct a knock-down barrel 65 wherein certain of the staves may be moved out of position to afford access to a rotatable member within the barrel, by first unfastening a peripherally disposed reinforcing means and opening end hinged locking 70 members which engage over the ends of said staves when the barrel is in closed position.

It is an object of this invention to provide a collapsible reel barrel wherein stationary partitions are mounted to afford a plurality of compartments wherein a number of different kinds of materials may be simultaneously wound for shipment upon a rotatable reel shaft journaled in the ends of 80 the barrel and axially projecting through the various compartments.

It is an important object of this invention to construct an externally reinforced knock-down barrel simple in form and provided 85 with a plurality of chambers in which materials of different kinds may be placed for shipment or storage.

Other and further important objects of the invention will be apparent from the 90 disclosures in the drawings and specification.

The invention (in a preferred form) is illustrated in the drawings and hereinafter more fully described.

95

On the drawings:

Figure 1 is an end view of a collapsible reel barrel embodying the principles of my invention, showing the same in open position to permit access to the interior of the 100 barrel.

Fig. 2 is a side view thereof looking toward the opening.

Fig. 3 is a section taken on line 3—3, of Fig. 1, with parts broken away.

Fig. 4 is a section taken on line 4—4, of Fig. 1.

Fig. 5 is a section taken on line 5—5, of Fig. 4, with parts omitted.

Fig. 6 is a fragmentary detail section 110 taken through the locking member at one end of the barrel.

Fig. 7 is an enlarged detail section taken on line 7—7, of Fig. 2.

As shown on the drawings:

The collapsible reel barrel comprises a plurality of similarly constructed complementally shaped transversely curved staves 1, made of wood or other suitable material forming the main or body portion of the barrel, said staves 1, are disposed in cylindrical relation between transversely curved end staves 2 and 3, when the barrel is assembled, said staves 2 and 3, being separated from one another to provide a side opening into the barrel adapted to be closed when desired by a plurality of transversely curved door staves 4, forming a flexible side door. One of the staves 4, is disposed to interfit with the end stave 2, while the other stave 4, is adapted to have its outer longitudinal edge interfit with the end stave 3, when the flexible side door is closed. One longitudinal edge of each of the staves 1, 2, 3 and 4, is grooved or concaved in shape and the opposite edge thereof is convex, as clearly shown in Fig. 5, so that any number of staves may be arranged to interfit with one another and the curvature of the interfitting portions of the staves permits a certain amount of relative movement therebetween without causing a separation or opening which, when the device is assembled, would afford a means of loss of the contents of the barrel.

To flexibly connect the staves 1, 2, 3, and 4, one to another, and to permit the staves 4, to be used as a side door for the barrel, each of the staves is provided with a number of apertures extending transversely therethrough from the convex to the concave edge respectively, said apertures of each stave being arranged to register with the apertures in the staves adjacent thereto, to permit flexible steel wires or cables 5, to be threaded through the registering apertures. One end of each of the cables 5, is secured by any suitable means in the convex edge of the end door stave 4, while the other end of each of the cables 5, is secured in the concave edge of the end stave 3, thus holding the barrel staves flexibly associated with one another to permit the same to be cylindrically grouped to form the side walls of the barrel.

To hold the side walls in cylindrical position to form the body of the barrel, a metallic end or reel head 6, is provided for each end of the barrel, the outer portion of which is bent outwardly at right angles to form a flange 7, having its rim or margin rolled, or curled outwardly from the flange as designated by the numeral 8, to afford a circumferential groove or recess into which the ends of the barrel staves engage, and having a portion of said flange 7, and the grooved portion 8, cut away to permit the

door staves 4, to be moved into closed position. Retaining bolts 9, are removably inserted through suitable apertures formed in the flanges 7, and in each end of the staves 1, 2 and 3, to rigidly hold the staves and barrel heads in assembled relation. Hingedly mounted on the outer surface of each of the reel heads 6, in a position to register with the ends of the side opening, and the cut away portion of said flange 7, and the grooved portion 8, is a locking member, the outer portion of which is bent upwardly at right angles to form a locking flange 12, the rim of which is rolled or curled as designated by the numeral 13, to afford an arc shaped groove to permit the respective ends of the door staves 4, to engage therein and be secured to the locking flange 12, by retaining bolts 9, removably engaged through the apertures in the ends of the door staves 4, and through suitable registering apertures in the locking flange 12.

Each of the staves 1, 2, 3, and 4, on the interior surface thereof is provided with a plurality of transverse grooves to form inner annular grooves to receive therein the edges of a plurality of centrally apertured partitions 14, adapted to divide the interior of the barrel into a number of compartments or chambers, as clearly shown in Figs. 2, 4, and 4, for a purpose hereinafter described.

An apertured bearing plate 15, is rigidly secured centrally on each of the reel heads 6, and journaled therein and projecting outwardly therefrom are the squared ends 16, of a rotatable reel shaft 17, axially disposed within the barrel and projecting through the stationary partitions 14, said heads 6, and the shaft 17, forming a reel. For the purpose of reinforcing the barrel after it has been assembled with the side door and locking members closed, a pair or set of hoops, chains or belts are circumferentially disposed a short distance from one another around the middle portion of the barrel, and have one end removably secured by means of a bolt 10, or other suitable means to the end stave 3, to prevent sliding of the belts. Each belt comprises a plurality of arc shaped or curved angle iron links 18, arranged alternately with respect to one another to permit the apertured adjacent ends of the longer sides thereof which are disposed at right angles to the barrel staves to be pivotally and removably secured together by bolts 19, or other suitable means and with the shorter sides, which are of a length equal to the width of the barrel staves, resting or bearing flatly against the outer surfaces of the barrel staves, alternately disposed on opposite sides of the rail or ridge formed by the connected longer sides of said links, said rails affording a suitable bearing means upon which the barrel may be rolled, and also permitting the barrel to be easily

tilted or turned while at rest or when the same is being rolled. To permit the belts to be tightly drawn around the barrel, the ends of the belts are provided with a turnbuckle or other suitable mechanism (not shown).

The operation is as follows:

With the various parts of the collapsible barrel formed as described the assembly of the same is very simple. The staves 1, 2, 3 and 4, being connected by the cables 5, are laid flat upon the ground with the transversely grooved sides up, in which position one of the reel heads 6, with its hinged locking member 11, open, may be secured to the staves 1, 2 and 3, by means of the bolts 9, with the ends of the said staves engaged in the grooved portion 8, of the reel head, and with the locking member 11, thereof registering with the cut away portion of the reel head and the side opening of the barrel formed when the door staves 4, are in open position as shown in Fig. 1. The partitions 14, may now be inserted through the open end of the barrel to engage in the annular grooves formed by the transverse grooves of the barrel staves. The rotatable reel shaft 17, is now inserted into the barrel through the partitions 14, with one of its squared ends 16, projecting through the bearing plate 15, of the reel head 6, already in position. The opposite reel head 6, is next secured in position by bolts 9, with the hinged locking member 11, thereof, also registering with the side opening of the barrel, thus affording a suitable opening in the barrel to permit materials of different kinds if desired to be placed in the various barrel compartments for shipment or storage.

The rotatable reel shaft 17, is used when it is desired to ship, or store materials such as cloth of different kinds, wires, cables or other articles adapted to be wound or wrapped upon the reel. With one end of the cloth or article to be stored in each of the barrel compartments attached to the shaft 17, a handle, crank or other suitable means is engaged on one or both of the squared ends of the shaft, which is rotated, thus simultaneously winding the articles upon the shaft in their respective compartments. The door staves 4, are now moved into position to close the side opening of the barrel, and the hinged locking members 11, closed to permit the curled portions 13, thereof, to engage over the ends of the staves 4, and be locked therewith by means of bolts 9. The belts formed by the links 18, are now disposed around the barrel, a short distance from one another, to reinforce the same, said belts having the ends thereof detachably secured together by means of the turnbuckle, thus permitting the belts to be drawn tightly around the barrel, and providing a pair of annular

rails about the barrel to permit the barrel to be rolled thereon, keeping the barrel staves clear, and also affording a means for easily tilting or turning the barrel when the same is being rolled, which in barrels of cylindrical form is usually a difficult matter to perform.

It will be seen that the collapsible barrel may readily be taken apart to permit the same to be compactly assembled in knock-down form for shipment or storage when the same is not in use.

I am aware that various details of construction may be varied through a wide range without departing from the principles of this invention, and I therefore do not purpose limiting the patent granted otherwise than necessitated by the prior art.

I claim as my invention:

1. In a collapsible barrel of the class described, a flexible body portion, means having openings therein removably secured thereto for closing the ends thereof to form a rigid construction, locking members forming a part of said means adapted to close said openings and lock the barrel, and rotatable means journaled in said means to form a reel adapted to have materials wound thereon for shipment.

2. In a collapsible barrel of the class described, a plurality of staves, means flexibly engaging the same one to another, head members having openings therein removably secured to the ends of said staves to form a rigid barrel, closure means forming a part of said head members to close the openings therein and engage certain of said staves to hold the barrel locked, rotatable means axially disposed within said barrel journaled in said head members to form a reel to permit materials to be wound thereon, and means disposed around said barrel to reinforce the same and permit tilting and turning thereof when the barrel is being rolled.

3. A collapsible barrel of the class described comprising interfitting staves, means flexibly connecting the same one to another, members having openings therein removably secured to said staves to close the ends of the barrel and form a rigid construction, said openings permitting certain of said staves to be moved to afford access to the interior of said barrel, partitions within the barrel for forming compartments therein, and externally operable means projecting through said partitions and journaled in said end members for simultaneously winding materials for shipment thereon in each of said compartments.

4. A collapsible barrel of the class described comprising a flexible body portion, barrel heads engaging over the ends thereof and removably secured thereto, a door in said flexible body portion to afford a means

- for placing materials within the barrel for shipment, and hinged locking members forming a part of said barrel heads adapted to engage said door to hold the same closed.
5. A collapsible barrel of the class described comprising flexibly connected interfitting staves, a flexible door connected with said staves to permit access into said barrel, end members removably secured to said staves to form a rigid construction and close the ends of the barrel, and a hinged member forming part of each of said end members adapted to engage over the ends of said flexible door when the same is closed and be removably secured thereto to tightly close the barrel.
6. In a collapsible barrel of the class described, flexibly connected interfitting staves, the end staves of which are spaced from one another to form a side opening for the barrel, door staves flexibly connected with one of the end staves to form a side door for closing said side opening, barrel heads removably secured to said interfitting staves having openings therein registering with said side opening, end locking members on said barrel heads to close said end openings and engage over the ends of said side door to completely close the barrel, rotatable means within the barrel journaled in said barrel heads to permit materials to be wound thereon when said locking members and door are open, and linked members removably engaged around said interfitting staves and said door staves when the barrel is closed to reinforce the same and afford a means for tilting and turning the barrel when it is rolled.
7. In a collapsible device of the class described comprising connected interfitting staves forming the body of the device, end members removably secured thereto, locking means forming a part thereof, and a door in said body to afford access into the device registering with said locking means and adapted to be engaged thereby for maintaining the device closed.
8. In a knock-down barrel of the class described, a flexible body portion, end members removably engaged thereover, a door in said body portion to afford access into said barrel when the same is open, means within said barrel for dividing the same into chambers, rotatable means projecting therethrough and journaled in said end members for winding different materials thereon in each of said chambers, and removable reinforcing means for said barrel when the same is closed for shipment.
9. In a collapsible barrel of the class described, a flexible body portion having an opening therein, a flexible door for closing said opening, end members for closing the ends of said body portion each having an opening therein registering with the opening in said body portion to permit said flexible door to open and close, and means for closing the openings in said end members and engaging the ends of said door to lock the same in closed position.

In testimony whereof I have hereunto subscribed my name in the presence of two subscribing witnesses.

THOMAS W. CORKELL.
